UNITED STATES PATENT OFFICE

2,514,537

PRIVY SEAT

Bertram L. Cullum, Atlanta, Ga., assignor of one-half to George P. Hardin, Atlanta, Ga.

Application July 9, 1947, Serial No. 759,736

2 Claims. (Cl. 4—237)

1

My invention relates to a seat for outdoor toilets or privies.

A primary object of the invention is to provide a seat for outdoor toilets or privies which is light, comfortable, sanitary, and inexpensive to manufacture.

A further object of the invention is to provide a seat having means to prevent insects or vermin from attacking the user of such seat.

A further object is to provide a device of the above mentioned character formed of material which is smooth to the touch and very readily cleaned.

A still further object is to provide a removable privy seat having liquid insecticide carrying means, and means to facilitate the replenishment of such liquid insecticide without removing the seat from the privy.

Other objects and advantages of the invention will be apparent during the course of the following description.

In the accompanying drawings, forming a part of this application, and in which like numerals are employed to designate like parts throughout the same,

Figure 1 is a perspective view of the privy seat embodying my invention, showing the seat cover in a partially raised position.

Figure 2 is a central vertical longitudinal section through the seat, the same being shown in position in a privy, the seat cover being shown closed.

Figure 3 is a fragmentary vertical section taken on line 3—3 of Figure 2, and,

Figure 4 is a reduced horizontal section taken on line 4—4 of Figure 2.

In the drawings, where for the purpose of illustration is shown a preferred embodiment of my invention, the numeral 10 designates a vertical plank forming part of the seat structure of a privy. The privy seat structure also includes a horizontal member or plank 11 having the usual hole 12.

Removably mounted upon the privy seat structure is a generally flat horizontal rectangular seat member 13, preferably formed of suitable plastics material, and provided with a forward depending flange or skirt 14, formed integral therewith, and providing a large smooth radius 14'. The horizontal seat member 13 has the usual seat hole 15, and this hole 15 has its upper edge rounded as at 16. A raised portion or shoulder 17 is provided near the rear end of the seat member 13, and this raised shoulder extends laterally across the seat member. Hinges 18 are

provided near the opposite ends of the raised shoulder 17 and are securely mounted thereon. These hinges are attached to a hinged seat cover 19, which is preferably rectangular and flat, and formed of plastics material. The seat cover 19 is provided with a central recess or notch 20 in its lower surface and forward end, to serve as a finger grip for lifting the cover 19. The rear edge of the hinged cover 19 is disposed adjacent to the forward edge of the raised shoulder 17 when the cover is in the closed position, Figure 2, and the arrangement of the hinges 18 upon the shoulder 17 permits the cover 19 to lie flat upon the seat member 13.

15 The numeral 21 designates a tubular downwardly flared skirt, preferably circular in horizontal cross section, and this skirt includes an annular horizontal flange 22 to engage the lower surface of the seat member 13. The tubular skirt 21 is rigidly secured to the horizontal seat member 13 by means of screws 23, or the like, and the hole 15 in the seat member registers with the inside diameter of the flange 22 in assembly, to form a smooth inner surface free 25 from recesses or cavities. The skirt 21 extends downwardly from the seat member 13 for a substantial distance, and is provided at its lower end with an external annular U-shaped insecticide trough 24 formed integral therewith. This trough 24 is preferably semi-circular in transverse cross section. The skirt 21 is formed of plastics material. The flaring side of the tubular skirt 21 has a small opening 25 near the vertical center of such side, and this opening is maintained closed from the outside by means of a cover 26. The cover 26 is securely attached near the lower end of a suitable leaf spring 27, which in turn is securely mounted upon the external surface of the skirt, 21, Figure 3. The opening 25 is recessed from the outside, forming a shoulder 25' to engage the forward face of the cover 26.

30 In use, the device is mounted upon the seat structure of a privy, as shown in Figure 2, and the seat member 13 rests upon the horizontal member 11. The depending flange 14 may engage the vertical member 10 of the privy. This arrangement prevents the user of the privy from contacting with splinters, or the like. The flared tubular skirt 21 is disposed within the hole 12 of 35 the privy, and the cleanliness or sanitation of the device is increased due to the fact that the skirt 21 flares outwardly toward its lower end. The annular trough 24 may be filled with a liquid insecticide while the seat is in place within the privy.

40 In order to fill or refill the trough with insecti-

55

cide, it is merely necessary to insert the neck of a bottle through the opening 25 from the inside of the skirt 21. The spring 27 carrying the cover 26 will yield when the bottle neck engages the cover 26, and the cover will swing outwardly. The insecticide may then be poured down the side of the skirt 21 and into the trough 24. In filling the trough, the holder of the bottle projects the same through the opening 15, and it is unnecessary to touch the device with the hands. When the bottle containing the insecticide is withdrawn from the opening 25, the cover 26 will snap shut automatically to cover the opening. The purpose of the insecticide trough 24 is to prevent vermin or insects from attacking the user of the privy seat. In order to do this the insects would have to travel down the outer surface of the flared skirt 21 and through the trough containing the liquid insecticide where they would be exterminated. The device may be removed bodily from the privy when desired, and it is quite light. Since the device is formed entirely of plastics material it is smooth and very easily cleaned.

It is to be understood that the form of my invention herewith shown and described is to be taken as a preferred example of the same, and that various changes in the shape, size, and arrangement of parts may be resorted to, without departing from the spirit of my invention or the scope of the subjoined claims.

Having thus described my invention, what I claim is:

1. A privy seat, comprising a seat member having an opening therein, an annular skirt secured to the seat member adjacent to the opening and depending therefrom and being longitudinally tapered and increasing in diameter toward its lower end and having a side opening, the lower end of the annular skirt being open, a substantially horizontal external trough secured to the lower end of the annular skirt and surrounding the same and adapted to receive a liquid insecticide, the trough being disposed radially outwardly of the side opening, a closure member dis-

posed upon the outer side of the skirt adjacent to the side opening for covering the same, and a spring secured to the skirt for moving the closure member inwardly to seat the same, the arrangement being such that the closure member may be moved outwardly by a container held within the skirt and opens outwardly when engaged by the container so that liquid insecticide may be poured down the outside of the skirt.

10. 2. A privy seat, comprising a seat member having an opening formed therein, an annular skirt secured to the seat member adjacent to the opening and depending therefrom and being longitudinally tapered and increasing in diameter downwardly and having a side opening, the lower end of the annular skirt being open, the skirt being bent at its lower end to form a substantially horizontal integral external trough surrounding the skirt and adapted to receive a liquid insecticide, the trough being disposed radially outwardly of the side opening, a closure member mounted upon the outer side of the skirt adjacent to the side opening for covering the same, and a spring secured to the skirt for moving the closure member inwardly to seat the same, the arrangement being such that the closure member may be moved outwardly by a container held within the skirt and opens outwardly when engaged by the container so that the liquid insecticide from the container may be poured down the outside of the flared skirt and into the trough.
